UNITED STATES PATENT OFFICE.

HUMPHREY M. GIBSON, OF CHICAGO, ILLINOIS, ASSIGNOR OF ONE-HALF TO HANS VON GOETZ, OF CHICAGO, ILLINOIS.

CHROMOTROPE.

1,182,266.

Specification of Letters Patent.

Patented May 9, 1916.

Application filed June 16, 1915. Serial No. 34,490.

To all whom it may concern:

Be it known that I, HUMPHREY M. GIBSON, a citizen of the United States, residing at Chicago, in the county of Cook and State 5 of Illinois, have invented certain new and useful Improvements in Chromotropes, of which the following is a specification.

This invention contemplates certain improvements in chromotropes and actuating 10 mechanism therefor, such as are used for advertising purposes.

The objects of the invention are to provide in a chromotrope one or more translucent disks which will prevent the observer 15 from seeing the electric light within the casing; to provide improved means comprising peripherally grooved rollers for supporting and rotating the disks; to provide a protective peripheral binding for each 20 disk to engage with the said supporting rollers; and to provide improved means for driving the rollers to rotate the disks in opposite directions.

In the accompanying drawings, Figure 1 25 is a front elevation of a device embodying the features of my invention. Fig. 2 is an enlarged vertical section. Fig. 3 is a vertical section taken in a plane at right angles to Fig. 2. Fig. 4 is a fragmental plan view 30 showing the disk-supporting rollers and the driving means therefor.

The device comprises a casing 5 having in opposite sides circular openings 6 which may, if desired, be closed by panes of transparent glass 7. Located within the casing behind each of the openings 6 is a pair of disks 8, preferably of glass, each disk having an ornamentation of suitable color and design, so that when the disks are rotated 35 in opposite directions, a variety of color effects will be produced, as is well known. Between the two pairs of disks is a suitable electric light fixture 9 carrying one or more lamps 10 by which the disks 8 are illuminated. The inner disk of each pair is made 40 translucent, as by frosting its inner face, so as to prevent the observer from seeing the lamps 10. The outer disk of each pair is of clear glass so that the design upon the 45 inner disk may be seen.

In the bottom of the casing is a closed box or support 11 in which is rotatably mounted a pair of horizontal shafts 12, one

shorter than the other. Each of these shafts has fixed on opposite ends two rollers 13 having V-grooves in their peripheries. The rollers lie in the different vertical planes of the disks 8 and the latter are supported and driven by said rollers. Each of the disks 8 has a peripheral protective binding 14 of metal or other suitable material and the weight of the disks acts to cause the binding to wedge in the peripheral groove of the roller so that a firm driving contact between the roller and the disk will be effected. 65 The disks are additionally guided or supported by grooved guides 15 located at opposite edges of the disks in a plane above the driving rollers 13.

A drive-shaft 16 is mounted in the support or box 11 at right angles to the shafts 12 and is driven by an electric motor 17. Said drive-shaft has two worms 18 thereon meshing with worm-wheels 19 on their respective shafts 12. The disks are differentially rotated; in this instance the worms and worm-wheels are pitched in opposite directions, so that the two shafts 12 will be oppositely rotated. The box 11 may be filled with a lubricant, if desired. 80

Obviously, one of the openings 6 and one pair of disks 8 and supporting rollers 13 may be omitted and the casing 5 narrowed correspondingly, if desired.

I claim as my invention:

1. A device of the character described comprising a casing having an opening therein, a pair of vertical circular disks positioned within the casing behind said opening, each disk having an ornamentation thereon, the disk next to the opening being of transparent material and the other disk being translucent, an artificial lighting device located within the casing behind said disks, each of the disks having a peripheral binding to protect its edge, two horizontal shafts rotatably mounted beneath said disks, two rollers, each fixed on one of said shafts in the plane of one of said disks, the rollers having V-grooves in their peripheries and the binding on said disks resting in said grooves, means for additionally guiding or supporting said disks, and means for driving said shafts in opposite directions. 85

2. A device of the class described comprising two rotary vertical disks positioned 100

side by side and each having a suitable ornamentation thereon, a casing inclosing said disks and having an opening through which the disks are visible, a lamp within the casing behind said disks, the disk next to the opening being of transparent material and the other disk being translucent to prevent

the observer from seeing said lamp, and means for differentially rotating said disks.

In testimony whereof, I hereunto set my hand in the presence of a witness.

HUMPHREY M. GIBSON.

In the presence of—

C. PAUL PARKER.
